UNITED STATES PATENT OFFICE.

WILLIAM E. DE VOE, OF DETROIT, MICHIGAN, ASSIGNOR TO THE UNDERFEED STOKER COMPANY OF AMERICA, OF DETROIT, MICHIGAN, A CORPORATION OF NEW JERSEY.

UNDERFEED FURNACE.

1,401,883.

Specification of Letters Patent. Patented Dec. 27, 1921.

Application filed November 5, 1920. Serial No. 422,044.

To all whom it may concern:

Be it known that I, WILLIAM E. De Voe, a citizen of the United States, residing at Detroit, in the county of Wayne and State 5 of Michigan, have invented certain new and useful Improvements in Underfeed Furnaces, of which the following is a specification.

My invention, pertaining to under-feed 10 furnaces, relates more particularly to stokers of the single-retort, lateral-dumping type having laterally-tiltable floor-sections, and it has for its objects to improve the operation of such stokers for some purposes, and to 15 provide simple, rugged and effective mechanism for operating the tilting floor-sections.

In the patents of Arthur H. Blackburn and Frank E. Fleming, No. 1,826,906 and No. 1,864,237, there are shown different 20 forms of tiltable floor-sections of a furnace of the type referred to, and for illustrative purposes I show my present invention applied to a stoker of construction like application Serial No. 262,252 as to its fire-box 25 floor. This furnace-construction in general being now well known, illustration and description thereof may be abbreviated.

In the drawings Figure 1 is a front elevation with parts in section of the furnace- 30 front; Fig. 2 is a cross section through the fire-box floor, showing normal position of the tilting parts; Fig. 3 is a similar view showing operating positions of such parts; Fig. 4 is generally a longitudinal section 35 with zones broken to different planes, the central portions being illustrated in a plane slightly to the right of index-line 4—4 of Fig. 1, and the extreme portions being broken to planes to the left of said index-line, and Figs. 5 and 6 are fragmentary 40 details.

In the type of stoker shown, fuel from 45 hopper 10 is fed by a suitable ram in casing 11 through throat 12 in the furnace-front-wall 13 into a longitudinal central retort 14 extending back to the bridge-wall 15 with its mouth horizontal; this retort having alongside of it, on one side thereof, two courses or series of laterally-tiltable floor- 50 elements 16 and 17 arranged in tandem laterally and pivoted as at 18, 19 respectively, along their outer edges so that their inner edges may be elevated to feeding, or load-avalanching angle. In normal position 55 these sections form part of the fire-box floor,

downsloping from the retort to substantially a line of juncture with the ash-dump gate 20, that is pivoted along its inner edge as at 21 upon a partition-wall structure 22 which divides the ash pit 23 from the wind-chamber 24 below the floor. Advantageously each inner floor-section 16 has an extension 16^a disposed to form a lip portion or extension of the retort 14, the body 14^a of which is rigid, such lip being provided with twyers 65 25, and each of the tiltable floor elements is provided with a skirt of arcuate section, as at 16^b, 17^b respectively, for known purpose. Of course the parts thus described, appurtenant to one side of the retort, are duplicated on the other, and so far as distinctive reference may be requisite those parts to the left, Fig. 1, will be identified by the prime-mark (').

It will be understood that I do not herein 75 claim the construction so far described *per se*, nor do I limit my invention specifically thereto, as other specific structures involving two series of laterally-tiltable floor elements disposed in tandem courses and 80 pivoted along their outer edges are known, and my operating mechanism may be applied thereto.

I provide, novelly, for tilting the two tandem courses of floor-sections singly and 85 alternately to cause the series of inner elements 16 to rise to its avalanching angle while the series of elements 17 is in normal position of rest, and vice versa; and I accomplish the result by means as follows: 90 Each tiltable element has near its inner edge a pivot pin, 26 or 27, and on these respectively act the upper ends of links 28 and 29. The links have at their lower ends pivot pins, 30, 31 that respectively engage opposite ends of a rocking lever 32 and that are of sufficient length also to engage and bear in saddles 34 and 35 of brackets 36 rigidly mounted at intervals on wall 22. If one rocks the lever 32 clockwise, outer pin 31 100 acts on saddle 35 as a fulcrum, pin 32 rising from its open saddle and elevating link 28, which pushes up the inner edge of the floor-element 16. Counterclockwise rocking of the lever 32 reverses this, pin 30 remaining 105 seated in its saddle (and floor elements 16 remaining in normal position) while outer link 19 and the inner edge of floor elements 17 are raised.

To rock the levers 32 for all those mecha- 110

- nisms that may serve a series of longitudinally-spaced tilttable floor-sections, a single shaft is provided on each side of the retort, as at 40 and 40', centrally engaging and 5 rigid with each lever 32 or 32', and these shafts are provided with external operating-means organized to accommodate the movements of the shafts incident to the described rocking-action. Thus, Fig. 1, the two shafts 10 are connected for engine-impelled operation in unison, the two shafts having fixed thereto levers or crank-arms 41, 41' for rocking them, these levers having their power-ends connected with respective links 42, 42' that 15 are pivoted also to the lower and upper arms of a centrally pivoted lever 43, mounted on the furnace front. The shaft 40 extends through a keyhole-aperture 45 (Fig. 5) in the front wall, shaped to give requisite clearance, and on the shaft is mounted a cover plate 46 pressed against the front wall by spring 47, to cover the opening 45. Of course, power may be applied to any suitable point of the exterior lever system, and specifically 20 50 represents an extension arm of lever 41', connected by pivoted link 51 to the piston rod 52 of a suitable reciprocating engine 53 suitably mounted on the boiler-front. In operation, as piston rod 52 reciprocates both levers 41, 41' are rocked between dotted-line positions. Each such lever rocks lever 32 or 32', shaft 40 or 40' moving bodily as lever 32 or 32' tilts alternately on its two saddles or fulcra. Consequently 25 35 one series of floor elements, as 16, rocks while its companion series 17, rests, or vice versa.
- I claim:
1. The combination with an underfeed stoker comprising a retort and two laterally-tiltable floor-elements arranged along one side of the retort, each said element being pivoted adjacent one edge, of reciprocatable means for rocking said elements singly and alternately comprising a rocking lever, two spaced fulcra therefor, means for rocking said lever on said fulcra alternately, and connections from said lever to the tilttable elements.
  2. In a device of the character described, a retort, two tilttable floor-elements arranged laterally beyond the retort, each pivoted along one edge, a rocking lever, two fulcra therefor, means for rocking said lever on its fulcra alternately and links, connected with the free edges of the floor-elements and with points on said rocking lever adjacent said fulcra.
  3. The combination with an underfeed stoker comprising a retort and two laterally-tiltable floor-elements laterally beyond the retort, each said element being pivoted adjacent one edge, of two operating links connected with the free edges of the respective floor-elements, an operating lever connected at opposite ends to the two operating links and having fulcra on which it may rock adjacent its opposite ends, and means for rocking said lever.
  4. The combination with a furnace having a front having a shaft opening, a longitudinal retort and two tilttable floor-elements arranged in tandem at one side of the retort, each said element being pivoted near its outer edge, links respectively connected with the free inner edges of the said members, a rocking lever to which said links are connected, and two saddles on which said lever may rock, adjacent the two link-connections, a shaft for rocking said lever, extending freely through said shaft-opening in the furnace front and bodily movable therein, and an engine outside of the furnace for actuating said shaft.
  5. The combination with a furnace having a front having a shaft opening, a longitudinal retort and two tilttable floor-elements arranged in tandem to one side of the retort, each said element being tilttable near its outer edge, links respectively connected with the free inner edges of the said members, a rocking lever to which said links are connected, and two saddles on which said lever may rock, adjacent the two link-connections, a shaft for rocking said lever, extending freely through said shaft-opening in the furnace front and bodily movable therein, a cover plate for said shaft-opening carried by the shaft, and an engine outside of the furnace for actuating said shaft.

WILLIAM E. DE VOE.
